UNITED STATES PATENT OFFICE.

GEORGE W. KOCH, OF PHILADELPHIA, PENNSYLVANIA.

BOTTLE WASHING AND RINSING MACHINE.

1,055,760.

Specification of Letters Patent. Patented Mar. 11, 1913.

Application filed May 11, 1911. Serial No. 626,650.

To all whom it may concern:

Be it known that I, GEORGE W. KOCH, a citizen of the United States, residing in Philadelphia, Pennsylvania, have invented 5 certain Improvements in Bottle Washing and Rinsing Machines, of which the following is a specification.

My invention relates to that class of bottle washing and rinsing machines in which 10 rows of bottles are carried by an endless conveyer in order that the rows of bottles may be presented successively to the bottle washing and rinsing devices, the object of 15 my invention being to construct a simple machine of this type which can be constructed at small cost compared with the capacity of the machine, and in which the thorough brush washing of each bottle can be effected and the bottles can be rinsed both 20 before and after the brush washing, the machine requiring no skilled attendance and being therefore operated with a minimum of expense.

In the accompanying drawings—Figure 25 1 is a side elevation of my improved bottle washing and rinsing machine, looking in the direction of the arrow *x*, Fig. 4; Fig. 2 is a side elevation of the machine looking in the direction of the arrow *y*, Fig. 4; Fig. 3 is a 30 central longitudinal vertical section of the machine; Fig. 4 is a vertical transverse section looking in the direction of the arrow *w*, Fig. 3; Fig. 5 is an enlarged transverse section on the line *a*—*a*, Fig. 3; Fig. 6 is an 35 enlarged transverse section on the line *b*—*b*, Fig. 3; Fig. 7 is a transverse section of part of the bottle carrier illustrating a special construction of the same, and Fig. 8 is an enlarged section of part of one of the presser 40 arms whereby the bottles are retained in position during the brush washing.

The machine has opposite side frames 1—1 providing bearings for transverse shafts 2, 3, 4, 5 and 6. The pulley 7 for receiving the driving belt is carried by a sleeve 7^a which can turn loosely on the projecting end of the shaft 2, and upon this sleeve is also mounted a spur wheel 9 and a spur pinion 10. The spur wheel 9 meshes with a 45 spur wheel 11 at one end of the shaft 5 and the spur pinion 10 meshes with a spur wheel 12 at one end of the shaft 3, as shown in Fig. 1. At the other end of said shaft 3 is a pinion 13 which meshes with a 50 internal annular rack 14 on a disk 15, the latter having on its periphery a toothed 55

segment 16 which meshes with similar toothed segments 17 on a disk 17^a; this disk having between the segments 17 concave peripheral segments 17^b which are engaged by 60 the convex portion of the periphery of the disk 15 whenever the toothed segment 16 of the latter is not in mesh with one of the segments 17 of the disk 17^a, whereby on each rotation of the disk 15 movement of partial 65 rotation will be imparted to the disk 17^a and the latter will be locked in position between its successive movements. The disk 17^a is mounted upon the hub of a disk 19 which is keyed to the shaft 2, said disks 17^a and 19 70 being secured together by means of bolts 20 which are adapted to slots 21 in the disk 17^a so that a limited amount of rotary motion of the two disks in respect to one another will be permitted when the nuts upon said bolts 75 have been loosened. (See Figs. 2 and 5).

The shaft 2 carries sprocket wheels 22 which engage with endless chains 23, the latter having anti-friction rollers 24 which travel upon runways 25 secured to or forming part 80 of the side frames 1 and projecting inwardly therefrom, as shown in Fig. 4. At one end of the machine each of these runways is discontinued in order to provide for the insertion of a drum 26 over which the endless 85 chain passes, these drums being mounted upon the shaft 6, and bearings for said shaft being free to slide in guides 27 on the side frames 1 and being acted upon by adjusting screws 29, so that the drums 26 can be moved 90 outwardly in order to impart the proper degree of tension to the endless chains 23. (See Figs. 1 to 3).

The endless chains 23 carry a series of 95 transverse rectangular frames 30, each having at the top a series of openings for receiving a row of bottles, and each frame being provided on the bottom with a corresponding series of tapered sockets 31 for receiving the mouths of said row of bottles, each socket having a tubular plug 32 guided radially in the base, so that the plug is free to move radially in the socket, the plug being acted upon by a coiled spring 33 which tends to press the plug 32 outwardly at all 100 times but permits the plug to yield inwardly to accommodate different lengths of bottles. (See Fig. 6).

In order to adapt the frames 30 for the reception of bottles of different diameters, 110 each of said frames may have on the top at each end a stud or button 30^a for engagement

with the corresponding end of a supplementary top bar 30^a, as shown in Fig. 7, this supplementary top bar having openings registering with, but of lesser diameter than, the openings in the main top bar of the frame, the supplementary top bar being held in position by springing its ends under the studs 30^a, and said ends being also notched, if desired, for engagement with said studs 10 to prevent lateral displacement. A central bolt 30^c may also be provided, said bolt having a nut for bearing upon the supplementary top bar to retain or aid in retaining the same in position.

15 The shaft 4 has, at one end, a lever 34, one arm of which is connected by a link 35 to a radially adjustable crank pin 36 on the disk 15, as shown in Fig. 2, whereby, as said disk rotates, rocking movement will be imparted to the shaft 4. The shaft 4 carries a pair of levers 37 which are connected to a counterweight 39, each of these levers being also connected by a link 40 to a bolt 41 which connects the upper and lower members 42 20 and 43 of a frame on which are mounted the brush spindles 44, these brush spindles having at their lower ends sleeves 45 adapted to bearings in the upper bar 42. Each sleeve 45 is provided with a spur pinion 46, the 25 spur pinions of a series of brush spindles intermeshing and the outer pinions of the set meshing with a spur wheel 47 which is splined to a vertical shaft 49 mounted in bearings on one of the side frames and carrying, 30 at its upper end, a bevel pinion 50 which meshes with a bevel pinion 51 on the shaft 5.

The frame comprising the upper and lower members 42 and 43 carries two rows of brush spindles 44, as shown in Fig. 3, or 40 it may have but one row or more than two, the spur wheel 47 of the shaft 49 driving the pinions 46 of one half of each of these rows of brush spindles, as shown in Fig. 4, so that the power necessary to rotate one half of the 45 spindles is derived from one end of the shaft 3 and that necessary to rotate the other half of the spindles is derived from the other end of said shaft, whereby the power is evenly distributed and excessive torsional strain 50 upon said shaft 3 is avoided.

By reason of the mechanism described the brush spindles are constantly rotated and are also raised and lowered at intervals. Each brush spindle has, at its upper end, a 55 brush 52 which, when the brush spindles are retracted, occupies a position within a tube 53 depending from a fixed cross bar 54, extending between the opposite side frames of the machine, as shown in Figs. 3 and 4, but 60 when the brush spindles are raised or projected the brush 52 emerges from this depending tube and passes through an opening 55 in the cross bar 54 and thence through the tube 32 of the socket 31 and into the inverted bottle which is supported by said

socket, the brush expanding by centrifugal force as soon as it enters the bottle so as to contact with all portions of the sides of the interior of said bottle.

Water for washing purposes is supplied to 70 the brushes in the following manner: The lower member 43 of the frame which carries the brush spindles has, at the top, a series of tubular step bearings 56 one for each of the sleeves 45 at the lower end of the brush spindles. The lower member 43 of the frame is hollow and is in communication with a transverse water supply pipe 57 by means of a flexible hose 59 and suitable couplings, the transverse pipe 57 also communicating with 75 a pipe 60 at one side of the machine, which pipe has a valve with arm 61 connected by a link 62 to an arm 63 on a rock shaft 64 adapted to bearings in the opposite sides of a head 65 mounted upon the opposite side frames of the machine and extending across the same from side to side. The arm 63 is also provided with a depending rod 66 having an outwardly bent lower end which is 80 acted upon at suitable intervals by one arm of the lever 34 on the shaft 4, as shown in Figs. 2 and 4. As the frame member 43 rises and the brushes are forced into the bottles the valve in the pipe 60 will be opened and water under pressure will be admitted to the lower member 43 and will thence pass through the various hollow brush connections to the brushes, the valve being closed and the flow of water cut off as the 85 brushes are withdrawn from the bottles, thereby preventing waste of water.

As the endless chain of bottle-carrying frames 30 is moved forward by a series of intermittent movements each row of bottles is subjected to the washing action first of one row of brushes and then of the next row of the same, whereby each bottle receives two brush washings. Before receiving the first brush washing each bottle receives a stream of water from a nozzle on the transverse pipe 57 which serves to rinse from said bottle any remaining portions of the caustic alkali solution in which it is customary to soak the bottles before washing them, and after receiving the second brush washing 100 each row of bottles is, at the next step in its forward movement, brought over another row of nozzles projecting upwardly from a pipe 67 which is in communication with the pipe 57, whereby, at the same time that each row of bottles is being acted upon by the brushes, a row of bottles in the rear and a row of bottles in advance will be receiving streams of water from the nozzles on the pipes 57 and 67, the unwashed bottles being 105 thereby freed from the soaking solution and the washed bottles being rinsed.

The means for holding down the bottles while the brushes are being raised into the same are shown in Figs. 1, 2, 3 and 4, and 110

are as follows: Above the bottoms of the inverted bottles and centrally disposed in respect to the two rows of brush spindles is a shaft 68 suitably guided at each end so as to be free to rise and fall, and pivotally mounted upon this shaft are a series of pairs of arms 69 whose lower ends are provided with pads 69^a (see Fig. 8) of rubber or other resilient material, these pads resting upon the bottoms of the two rows of bottles which are in position for the action of the brushes 52, a spring 70 connecting the arms 69 of each pair and tending to draw them toward each other but permitting them to swing apart to any desired extent, depending upon the upward pressure imparted to each arm by contact with the bottom of the bottle when the shaft 68 is lowered, suitable means being provided for limiting the approach of the arms 69 toward each other.

The shaft 68 near each end, is connected by a rod 71 to an arm 72 on the rock shaft 64 so that as said shaft is rocked in one direction by the depression of the rod 66 by 25 the lever 34 the shaft 68 will descend and will press the pads 69^a at the lower end of the arms 69 upon the upturned bottoms of the two rows of bottles beneath the same, thereby pressing the mouths of said bottles 30 firmly into the sockets 31 of the frames which carry the bottles.

The freedom of each arm 69 to yield upwardly independently of the other arms causes proper uniform bearing of the pads 35 on the arms upon each bottle irrespective of slight differences in the length of the bottles, the lower ends of the arms bearing centrally upon the bottom of each bottle and thus overcoming any tendency to tip or tilt 40 the bottles out of their proper vertical position.

The frictional hold of the resilient pads 69^a upon the bottoms of the bottles prevents any tendency of said bottles to rotate under 45 the influence of the rotating brushes 52.

In the operation of the machine the attendant in charge of the soaking of the bottles applies the soaked bottles to the frames 30 at one end of the machine and 50 the attendant in charge of the filling machine removes the washed and rinsed bottles from the frames 30 at the other end of the machine, no further attendance being required.

55 By reason of the adjustable connection between the shaft 2 which carries the chain driving sprockets 22 and the disk 17^a whereby intermittent movements are imparted to said shaft 2, the chains 23 can be moved 60 backward or forward to a limited extent

independently of the means whereby the successive feed movements are imparted to the chains and the proper registry of the bottle-receiving sockets 31 in respect to the brushes can thereby be insured. 65

I claim:

1. The combination, in a bottle washing machine, of a row of brush spindles, a reciprocating frame carrying the same, rotating shafts at opposite sides of the machine, and gearing whereby one of said shafts operates the brush spindles on one side of the center of the carrying frame and the other shaft operates the brush spindles on the other side of said center. 75

2. The combination, in a bottle washing machine, of an endless chain of carriers, each adapted to receive a row of bottles, brush carrying spindles, one for each bottle of a row, a reciprocated frame carrying 80 said brush spindles, and a rising and falling shaft having a series of yieldingly mounted pairs of arms thereon, the arms of each pair bearing upon the bottoms of two adjoining rows of bottles when the brushes are entering the same. 85

3. The combination, in a bottle washing machine, of a bottle carrier having a bar with openings therein for receiving a row of bottles, and a supplementary bar superposed upon said first bar and having therein 90 a row of bottle-receiving openings of lesser diameter than those of the first bar, and means for detachably securing said supplementary bar upon the main bar of the 95 carrier with the openings of the two bars in registry with one another.

4. The combination, in a bottle washing machine, of an endless chain of bottle carriers, a shaft having thereon a gear wheel 100 for driving said chain and another gear wheel having toothed segments and locking segments alternating with one another, a reciprocating brush carrier, a wheel having external teeth for meshing successively 105 with said toothed segments, and a peripheral portion for engaging said locking segments, said wheel also having an internal drive gear and an external crank pin, and a connection between said crank pin and 110 an arm on a rock shaft, which has another arm connected to the reciprocating brush carrier.

In testimony whereof, I have signed my name to this specification, in the presence of 115 two subscribing witnesses.

GEORGE W. KOCH.
